UNITED STATES PATENT OFFICE.

LYMAN S. WARE, OF NORFOLK, MASSACHUSETTS.

WATER-GATE.

SPECIFICATION forming part of Letters Patent No. 240,564, dated April 26, 1881.

Application filed January 7, 1881. (No model.)

To all whom it may concern:

Be it known that I, LYMAN S. WARE, of the town and county of Norfolk, and State of Massachusetts, have invented a new and useful 5 Improvement in Flume or Sluice Gates; and I do hereby declare the same to be described in the following specification and represented in the accompanying drawings, of which—

Figure 1 is a front elevation, Fig. 2 an edge 10 view, Fig. 3 a vertical section, and Fig. 4 a transverse section, of a gate and its supporting-frame provided with my invention, the objects of which are to enable the gate to be easily moved under the pressure of water 15 against it, and to prevent wear of the joint-surfaces of the gate and its support-frame. Fig. 5 is a rear elevation of the gate, and Fig. 6 is a front elevation of its supporting-frame.

My said invention consists in the combination 20 of a sluice or flume gate, provided with edge and top flanges, with its supporting-frame, having edge-guides, friction-rollers, and a top flange, all being arranged substantially as set forth.

In the drawings, A denotes the gate, and B its supporting-frame, each being supposed to be of metal or other suitable material. The 25 said gate has projecting from its opposite parallel and longer edges two flanges, *a a*, each 30 being at a right angle to its edge of the gate. There also projects from the gate, at its upper end, and back from the rear face of such gate, a flange, *b*, which, at each extremity, extends somewhat beyond the next adjacent 35 longer edge of the gate, such being as shown in Fig. 5.

The gate-frame B has on its front face two parallel guides, *c c*, their distance apart being to correspond with the width of the gate, such 40 gate being arranged directly between them and by them, and guided by them in its rectilinear movements. In each of these guides, or arranged with them, as shown, is a series of friction-wheels, *d*, against the peripheries of 45 which the edge flanges *a a* of the gate bear.

Extending between the guides *c c*, and from the top of one to that of the other of them, and projecting from the front face of the gate-support frame, is a flange, *e*, upon the top of 50 which, when the gate is closed, the top flange of such gate rests.

When the gate is shut its lower end is to rest upon a sill or flange, *f*, extending from one to the other of the guides.

The gate-frame may be provided with holes 55 *g*, to receive bolts or spikes, for securing it to a flume or sluice.

From the above it will be seen that when the gate is closed, or when more or less open, or while it may be in movement, there will be 60 no material pressure and friction of the joint-surfaces of its longer edges against the guides, the pressure of water on the gate causing the edge flanges to bear on the peripheries of the friction-wheels, whereby, when the gate is in 65 the act of being either raised or lowered, it can be with little power and friction, in comparison to what would result were the flanges to bear directly against the guides unprovided with friction-wheels.

Thus, with my improvement, a gate can be worked to great advantage with little friction and wear of its joint-surfaces, and by a small expenditure of power, comparatively speaking.

The guides *c c* may be applied to the frame 75 B so as to be adjustable relatively to the bearing-edges of the gate, in order to admit of such guides being set up to the gate as it or they may become worn.

I am aware of the arrangement of friction-wheels and a gate within a sluice, as shown in the United States Patent No. 234,996, and do not claim such, for such shows no sluice-gate provided with edge or top flanges arranged with it, as are the edge flanges *a a* and top flanges, 85 *b*, of my improved gate. Nor does the said patent show any gate-supporting frame independently of the sluice, and having guides, a top flange, and friction-rollers arranged in it, and to operate with a gate having edge flanges 90 and a top flange, as hereinbefore described, and as represented in the accompanying drawings.

With my improvement the devices for supporting and guiding the gate are wholly outside of its vertical edges, and are not in the 95 sluice or flume to obstruct the water in passing into such. As my invention involves a gate-sustaining frame to be fastened to a flume, the top flanges, *b* and *e*, of such frame, and the gate become essential to the rest, no such 100 flanges being shown in the said patent. Therefore,

I claim—

1. The flume or sluice gate provided with the edge and top flanges, *a a b*, in combination with the gate-supporting frame, having the guides *e*, top flange, *e*, and friction-wheels *d*, all being arranged and adapted substantially as set forth.
- 5 2. The flume or sluice gate provided with the edge and top flanges, *a a b*, in combination

with the gate-supporting frame, having the guides *c*, top flange, *e*, bearing-sill *f*, and friction-rollers *d*, all being arranged and adapted substantially in manner and to operate as set forth.

LYMAN S. WARE.
